UNITED STATES PATENT OFFICE

2,505,188

LOCKING MEANS FOR DOOR LATCHES

Fred Kaiser, Brooklyn, N. Y.

Application March 30, 1949, Serial No. 84,343

10 Claims. (Cl. 70—210)

1

This invention relates to improvements in door latch mechanism including means operative from one, e. g. the inner, side of the door for locking the latch mechanism against manipulation from the opposite, e. g. the outer, side of the door.

It is the purpose of the invention to provide, in combination with a door latch mechanism which is operable by a spindle adapted to be rotated by the turning of the door knobs, means operative from the inner side of the door for locking the spindle against rotation by the outer door knob, but leaving said spindle subject to rotation by the inner door knob at all times; such means comprising a novel locking device which is mounted within the rose associated with the inner door knob and which is adapted to cooperate with a manipulatable lock-bar that is slidably mounted in connection with the spindle, said lock-bar terminating in a push button mounted in connection with the inner door knob so as to project axially therefrom, and by which the lock-bar can be manipulated. The invention further includes an arrangement whereby the lock-bar can be released from its spindle locking disposition by means of a push key adapted to be inserted into the outer knob.

An illustrative embodiment of the invention is shown in the accompanying drawings, in which:

Fig. 1 is a fragmentary inside face view of a door which is equipped with the novel latch mechanism and locking means therefor according to this invention; Fig. 2 is a vertical cross-sectional view, taken on line 2—2 in Fig. 1, the locking means being shown in released position; Fig. 3 is a transverse section, taken on line 3—3 in Fig. 2; Fig. 4 is another transverse section, taken on line 4—4 in Fig. 2; Fig. 5 is a vertical cross-sectional view, similar to that of Fig. 2, but showing the locking means in spindle locking condition; Fig. 6 is a transverse section, taken on line 6—6 in Fig. 5; Fig. 7 is a transverse section, similar to that of Fig. 6, but showing a released condition of the locking means as produced by the turning of the inner door knob; and Fig. 8 is a horizontal plan view in part section, taken on line 8—8 in Fig. 5.

Similar characters of reference are employed in the above described views, to indicate corresponding parts.

Referring to the drawings, the reference character 10 indicates a door equipped with a latch mechanism and locking means therefor according to this invention. Mounted in a mortised opening, which extends into the door body from its free end, is a casing 11 in which is housed

2

the normally projected door latch bolt 12. Journaled in and between opposite side walls of the casing 11 is the hub 13 of a rotary cam piece which is shaped to provide oppositely extending cam elements 14. Unitary with said latch bolt 12, to extend from the inner end thereof within the casing 11, is a pull member 15 which terminates at its rearward end in spaced apart legs 16 adapted to straddle the hub 13 of the cam piece. Said legs 16 of the pull member 15 are provided with terminal portions 17 which are suitably shaped for operative engagement by the cam elements 14. The pull member 15 extends through a transverse partition member 18 with which the interior of the casing 11 is provided at a point intermediate the cam piece and latch bolt. The latch bolt and its pull member is yieldably urged to latch bolt projecting position by a compression spring 19 which is engaged around the pull member between the inner or rear end of the door latch 12 and said partition member 18.

The means for operating the above described latch mechanism comprises a knob actuatable spindle which extends through the hub 13 of the cam piece from one side to the other of the door 10. Said spindle is formed to provide a main body section 20 of polygonal cross-sectional shape which extends through the hub 13 of the cam piece and thence toward and through the outer side of the door 10, and said hub 13 of the cam piece is provided with a correspondingly shaped axial opening 21, whereby said cam piece is keyed to the spindle to turn therewith. Unitary with and extending axially from the body section 20 of the spindle, toward and through the inner side of the door 10, is a tail section 22 of circular cross-section.

Affixed to the exterior face of the door 10 is an exterior rose 23 by which an exterior door knob 24 is rotatably supported. The shank of said knob 24 is provided with an axially disposed spindle receiving opening 24' of polygonal cross-sectional shape corresponding to the cross-sectional shape of the main body 20 of the spindle, 40 whereby said spindle is keyed to the knob to turn therewith.

Affixed to the interior face of the door 10 is an interior rose 25 by which an interior door knob 26 is rotatably supported. Countersunk in inner face of the body of the interior rose 25 is a perpendicular slideway or guide channel 27, and also countersunk in the body of said interior rose, so as to open toward the slideway or guide channel 27, is an axially disposed circular recess 55 28, with which communicates an outwardly ex-

tending axial bearing opening 29 of reduced diameter. The terminal hub 30 of the shank of the interior door knob 26 is journaled in said bearing opening 29. Housed in the recess 28 is a rotatable clutch-piece 31, which is provided with an outwardly extending, externally screw-threaded stem 32 of reduced diameter. Said clutch-piece 31 and its stem 32 is provided with an axial passage 33 through which extends the tail section 22 of the above described spindle. The shank of the interior door knob 26 is provided with an axially disposed internally screw-threaded opening 34, whereby said knob can be screwed onto and affixed to the stem 32 of the clutch-piece 31, so as to couple said clutch-piece and knob in unitary operative relation. The clutch-piece 31 is provided in its upper section or part with a radially extending clutch opening 35 of sectoral shape, behind which is disposed a stop shoulder 36 which is formed in connection with the stem 32 of said clutch-piece.

The spindle 20-22 is provided with an upwardly open guideway 37 which extends longitudinally therethrough from end to end thereof. Slidably supported in said guideway 37 is a longitudinally movable lock-bar 38, one end portion 39 of which projects outwardly from the tail section 22 of the spindle into the interior knob 26. Affixed to the extremity of said end portion 39 of the lock-bar 38 is a push-button 40, which projects exteriorly of the face of the interior knob 26. Formed in connection with the upper exposed edge of said lock-bar is an upwardly projecting lock-piece 41. This lock-piece is shaped to provide a forward inclined cam edge 42 and a rearward inclined cam edge 43. Behind the lock-piece 41, the lock-bar 38 is further provided with a stop projection 44 which normally abuts the stop-shoulder 36 of the clutch-piece, whereby to determine the normal initial retracted position of the lock-bar (see Fig. 2).

Slidably supported in the slideway or guide channel 27 of the interior rose 25, subject to movements therein in the perpendicular plane thereof, is a lock-plate 45, which is thus disposed transverse to the spindle and lock-bar 38. The lock-plate 45 is yieldably thrust downwardly by compression springs 46 to a normal stopped position against the bottom end 47 of the slideway or guide channel 27. Said compression springs 46 are housed in cavities 48, with which the body of the interior rose 25 is provided, respectively contiguous to opposite sides of the slideway or guide channel 27. Side marginal portions of the lock-plate 45 are cut away as at 49 to accommodate said springs 46, so that the upper extremities of the springs are backed against the upper ends 50 of the cavities 48, while the lower ends of the springs bear upon and thrust against shoulders 51 which are formed on the lock-plate 45 at the lower ends of the cut away portions 49. The central portion of the lock-plate 45 is cut away to provide an opening comprising an upper section 52, adapted to straddle the tail section 22 of the spindle, and a lower section 53 of enlarged dimensions and so shaped as to provide the lock-plate with lift projections 54 intermediate said upper and lower sections 51 and 52 of the opening at respectively opposite sides of the latter.

Formed in connection with the lower section or part of the clutch-piece 31, to project from the face thereof into the lower section 53 of the lock-plate opening, so as to lie intermediate and in normal engagement with the lift projections 54 of the lock-plate 45, is a cam element 55. The

top margin of the upper section 52 of the lock-plate opening is indented by a lock-notch 56 of a width corresponding to the thickness of the lock-bar 38 and its lock-piece 41. Preferably the interior rose 25 is provided with a cover plate 57 which overlies the slideway or guide channel 27 and the lock-plate 45 contained therein. Said cover plate 57 is provided with a suitably shaped central opening 58 through which the spindle extends, and through which the lock-bar 38 and its lock-piece 41 may pass. The lock-bar 38 is yieldably thrust to stopped normal position, determined by abutment of its stop projection 44 against the stop shoulder 36, by a compression spring 59 which is mounted around the end portion 39 of the lock-bar between the spindle and push button 40.

It will be understood that the roses 23 and 25 may be affixed to the respective exterior and interior faces of the door 10 in various ways. Preferably, however, as shown in Fig. 8, internally screw-threaded tie members 60 extend from the rose 23 through the door 10 to the rose 25, and fastening screws 61 pass through the latter to screw into said tie members 60, thus securely affixing the roses in place, and in such manner that removal thereof cannot be accomplished from the exterior side of the door.

Normally the lock-bar 38 is inwardly or rearwardly disposed in the normal position shown in Fig. 2 so that the push-button 40 is outwardly projected from the face of the interior door knob 26. When the lock-bar 38 is thus disposed, the lock-piece 41 is disengaged from the lock-notch 56 of the lock-plate 45, so that the spindle 20-22 is free to be turned by the exterior door knob 24 in either direction, thereby to operate the latch mechanism to effect door releasing retraction of the latch bolt 12. When the lock-bar 38 is disposed in said normal position, the lock-piece 41 lies wholly within the clutch opening 35 of the clutch-piece 31. When, therefore, the interior door knob 26 is turned in either direction, the clutch-piece 31 is also turned to engage a side of the clutch opening 35 thereof with the lock-piece 41, so that the rotary movement of the clutch-piece is transmitted through the lock-piece 41 and lock-bar 38 to the spindle 20-22, whereby the latter is turned so as to operate the latch mechanism to effect door releasing retraction of the latch bolt 12. It will thus be obvious that, under these circumstances, the spindle can be rotated to operate the latch mechanism by either the exterior or interior door knob, so that the door may be opened from either the outside or inside thereof.

If it is desired to lock the door against being opened from the outside, after the door is closed from the inside, the operator merely pushes inwardly upon the push button 40, thus sliding forwardly the lock-bar 38 along the spindle 20-22. Such forward movement of the lock-bar 38 carries forward the lock-piece 41, whereby its forward cam edge 42 engages and lifts the lock-plate 45 against the tension of the springs 46 so as to permit the peak of said lock-piece to pass the lock-plate for disposition forwardly of the latter, whereafter the lock-plate descends, under the influence of the springs 46, so that the lock-notch 56 thereof embraces the rearward portion of the lock-piece in interlocking relation thereto, with the consequence that the spindle 20-22 is restrained from operative rotation by the exterior door knob 24, and opening of the door by manipulation of the exterior door knob is prevented (see

Figs. 5 and 6). When the lock-bar 38 is thus forwardly moved, the peak of the lock-piece 41 will abut the face of the lowered lock-plate 45 above the end of the lock-notch 56, and the lock-bar will thereby be stopped against rearward or retractive movement under the influence of the spring 59. Such restraint is effective notwithstanding the engagement of the rear cam edge 43 of the lock-piece 41 with the lock-plate 45, since the tensional pressure of the springs 46, which thrust down the lock-plate, is greater than the tensional pressure of the spring 59.

When the spindle 20-22 is locked against latch mechanism operating rotation by the exterior door knob 24, if the interior door knob 26 is turned in either direction, the clutch-piece 31 will be rotated whereby its cam element 55 will cooperate with one or the other of the lift projections 54 of the lock-plate 45, thus lifting the latter against the tension of the springs 46, so as to disengage the lock-notch 56 from the lock-piece 41 of the lock-bar 38 (see Fig. 7). Owing to the sectoral shape and width of the clutch-opening 35 of the clutch-piece 31, the initial lock-plate lifting rotation of the clutch-piece and its cam element 55 will not be obstructed by the lock-piece 41, even though a portion of the latter lies within said clutch-opening 35, since an initial play between the sides of the clutch-opening and lock-piece 41 is provided for. As a consequence of this, the rotated clutch-piece will not transmit its motion to the lock-piece 41 and spindle 20-22 until after the lock-plate 45 has been lifted, and the lock-bar 38 set free for return to its normal initial or retracted position under the influence of its spring 59. Upon return of the lock-bar 38 to normal initial or retracted position, the retractive movement of the clutch-piece 31 is transmitted through the engaged lock-piece 41 to the spindle 20-22, whereby to effect latch mechanism operating relation of the latter by the interior door knob 26. By reason of this mode of operation, not only is the interior door knob 26 free for latch mechanism operation at all times, but also operation of said interior door knob automatically releases the exterior door knob 24 from locked condition if theretofore locked.

Since circumstances might occur under which it would be desirable or necessary to release the lock-bar 38 from the lock-plate 45 from the outer side of the door, means are provided for such purpose. This means comprises the provision in the face of the exterior knob 24 of a keyhole 63 which is aligned with the slideway 37 of the spindle portion 20, so as to be opposed to the forward extremity 62 of the lock-bar 28. Release of the lock-bar 38 and its lock-piece 41 from spindle locking relation to the lock-plate 45 may be effected from the outer side of the door by inserting a suitable push-key 64 through the keyhole 63 and into the slideway 37 so as to engage and thrust against the extremity 62 of the lock bar, whereby to push the latter rearwardly. As rearward movement of the lock-bar 38 is thus induced by the inserted push-key 64, the cam edge 43 of the lock-piece 41 is thrust against the lock-plate 45 so as to lift the latter against the tension of the springs 46, thereby allowing the peak of the lock-piece to be disengaged from the lock-notch 56, and thus permitting the spring 59 to return the lock-bar to normal initial or retracted position, so that the spindle 20-22 is thereupon freed and subject to latch mechanism operating rotation by the exterior door knob 24.

Having now described my invention, I claim:

1. Latch mechanism for a door comprising a latch bolt and actuating means therefor, a rose mounted on the inner side of the door, a yieldable lock-plate housed in said rose, a rotatable clutch-piece also housed in said rose behind the lock-plate, an interior door knob journaled in the rose and connected with said clutch-piece whereby to rotate the same, a spindle operatively engaged with the latch bolt actuating means, an exterior door knob affixed to the outer end portion of said spindle, the inner end portion of said spindle extending through the lock-plate and clutch-piece, a lock-bar slidably mounted on the spindle, an end portion of said lock-bar terminating in a push button disposed to project from the face of the interior door knob, and a lock-piece on said lock-bar, the lock-piece being engageable by the clutch-piece whereby to rotate the spindle when the interior door knob is turned, said lock-piece being adapted to be carried by forward shifting of the lock-bar into interlocked engagement with the lock-plate whereby to lock the spindle against rotation by the exterior door knob.
2. A latch mechanism for a door as defined in claim 1, wherein the lock-piece is provided with a forward cam edge formation operative to temporarily displace the lock-plate upon inward movement of the lock-piece to its interlocked relation to said lock-plate.
3. A latch mechanism for a door as defined in claim 1, wherein the exterior door knob is provided with a key receiving means whereby a key inserted therein may be utilized to engage and retract the lock-bar to withdraw the lock-piece from interlocked relation to the lock-plate, said lock-piece having a rearward cam edge formation operative to release the lock-plate from the lock-piece.
4. A latch mechanism for a door as defined in claim 1, wherein the lock-piece is provided with a forward cam edge formation operative to temporarily displace the lock-plate upon inward movement of the lock-piece to its interlocked relation to said lock-plate, and wherein the exterior door knob is provided with a key receiving means whereby a key inserted therein may be utilized to engage and retract the lock-bar to withdraw the lock-piece from interlocked relation to the lock-plate, said lock-piece having a rearward cam edge formation operative to release the lock-plate from the lock-piece.
5. Latch mechanism for a door comprising a latch bolt and actuating means therefor, a rose mounted on the inner side of the door, a yieldable lock-plate housed in said rose, a rotatable clutch-piece also housed in said rose behind the lock-plate, an interior door knob journaled in the rose and connected with said clutch-piece whereby to rotate the same, a spindle operatively engaged with the latch bolt actuating means, an exterior door knob affixed to the outer end portion of said spindle, the inner end portion of said spindle extending through the lock-plate and clutch-piece, a lock-bar slidably mounted on the spindle, an end portion of said lock-bar terminating in a push button disposed to project from the face of the interior door knob, a lock-piece on said lock-bar, the lock-piece being engageable by the clutch-piece whereby to rotate the spindle when the interior door knob is turned, said lock-piece being adapted to be carried by forward shifting of the lock-bar into interlocked engagement with the lock-plate whereby to lock

the spindle against rotation by the exterior door knob, said clutch-piece and lock-plate have co-operative means whereby initial rotative movement of the former will move the lock-plate to release the lock-piece from interlocked relation thereto, and spring means for retracting the lock-bar and lock-piece when so released.

6. Latch mechanism for a door comprising a latch bolt and actuating means therefor, a rose mounted on the inner side of the door, said rose having a slideway formed in its inner face, a spring-pressed lock-plate movable in said slideway, a clutch-piece rotatably mounted in said rose behind the lock-plate, an interior door knob journaled in the rose and affixed to said clutch-piece for rotating the latter, a spindle operatively engaged with the latch bolt actuating means, an exterior door knob affixed to one end portion of said spindle, the opposite end portion of said spindle extending through the lock-plate and clutch-piece, said spindle having a longitudinally extending slideway, a lock-bar slidably mounted in said spindle slideway, an end portion of said lock-bar terminating in a push button disposed to project from the face of the interior door knob, and a lock-piece projecting from said lock-bar and adapted to be engageable by the clutch-piece whereby to rotate the spindle by turning of the interior door knob, said lock-piece being adapted to be carried by forward shifting of the lock-bar into interlocked engagement with the lock-plate, whereby to lock the spindle against rotation by the exterior door knob.

7. Latch mechanism for a door comprising a latch bolt and actuating means therefor, a rose mounted on the inner side of the door, said rose having a slideway formed in its inner face, a spring-pressed lock-plate movable in said slideway, a clutch-piece rotatably mounted in said rose behind the lock-plate, an interior door knob journaled in the rose and affixed to said clutch-piece for rotating the latter, a spindle operatively engaged with the latch bolt actuating means, an exterior door knob affixed to one end portion of said spindle, the opposite end portion of said spindle extending through the lock-plate and clutch-piece, said spindle having a longitudinally extending slideway, a lock-bar slidably mounted in said spindle slideway, an end portion of said lock-bar terminating in a push button disposed to project from the face of the interior door knob, a lock-piece projecting from

said lock-bar and adapted to be engageable by the clutch-piece whereby to rotate the spindle by turning of the interior door knob, said lock-piece being adapted to be carried by forward shifting of the lock-bar into interlocked engagement with the lock-plate, whereby to lock the spindle against rotation by the exterior door knob, said clutch-piece and lock-plate having cooperative means whereby initial rotative movement of the former will move the lock-plate to release the lock-piece from interlocked relation thereto, and spring means for retracting the lock-bar and lock-piece when so released.

8. Latch mechanism for a door as defined in claim 7, wherein the lock-piece is provided with a forward cam edge formation operative to temporarily displace the lock-plate upon inward movement of the lock-piece to its interlocked relation to said lock-plate.

15 9. Latch mechanism for a door as defined in claim 7, wherein the exterior door knob is provided with a key receiving means whereby a key inserted therein may be utilized to engage and retract the lock-bar to withdraw the lock-piece from interlocked relation to the lock-plate, said lock-piece having a rearward cam edge formation operative to release the lock-plate from the lock-piece.

20 10. Latch mechanism for a door as defined in claim 7, wherein the lock-piece is provided with a forward cam edge formation operative to temporarily displace the lock-plate upon inward movement of the lock-piece to its interlocked relation to said lock-plate, and wherein the exterior door knob is provided with a key receiving means whereby a key inserted therein may be utilized to engage and retract the lock-bar to withdraw the lock-piece from interlocked relation to the lock-plate, said lock-piece having a 25 rearward cam edge formation operative to release the lock-plate from the lock-piece.

FRED KAISER.
